(57) **CLAIM**

The ornamental design for a safety interlock for a fire extinguisher, as shown and described.

DESCRIPTION

This application incorporates by reference in its entirety and claims priority from the following applications:

U.S. application Ser. No. 29/612,238 filed Jul. 31, 2017, entitled Fire Extinguisher, that issued as USD843,068 on Mar. 12, 2019;

U.S. application Ser. No. 29/505,639 filed Dec. 24, 2015, entitled Fire Extinguisher, that issued as USD796,121 on Aug. 29, 2017; and

U.S. application Ser. No. 29/526,021 filed May 5, 2015, entitled Fire Extinguisher, that issued as USD777,991 on Jan. 31, 2017.

FIG. 1 is a top right perspective view of a safety interlock for a fire extinguisher showing our new design;

FIG. 2 is a right-side view of the safety interlock for a fire extinguisher of FIG. 1 shown without the fire extinguisher, the left side view is a mirror image of the right side view; FIG. 3 is a front view of the safety interlock for a fire extinguisher of FIG. 2;

FIG. 4 is a rear view of the safety interlock for a fire extinguisher of FIG. 2;

FIG. 5 is a bottom view of the safety interlock for a fire extinguisher of FIG. 2;

FIG. 6 is a top view of the safety interlock for a fire extinguisher of FIG. 2;

FIG. 7 is a top left perspective view of the safety interlock for a fire extinguisher of FIG. 2; and,

FIG. 8 is a top left perspective view of the safety interlock for a fire extinguisher of FIG. 2 shown in an alternate configuration.

The features shown in broken lines in the figures depict environmental subject matter only and form no part of the claimed design.

1 Claim, 5 Drawing Sheets
